PAPER-TUBE SHOT-SHELL.

1,064,907.

Specification of Letters Patent.

Patented June 17, 1913.

Application filed April 4, 1913. Serial No. 758,771.

To all whom it may concern:

Be it known that I, FRANK O. HOAGLAND, a citizen of the United States, residing in Bridgeport, in the county of Fairfield and 5 State of Connecticut, have invented certain new and useful Improvements in Paper-Tube Shot-Shells, of which the following is a specification.

This invention relates to that special class 10 of reloadable shot-shells in which a metal head having a relatively short tubular portion is combined with a relatively long paper-tube extension, and a principal object of the invention is to furnish such shells 15 having a more effective inter-engagement between the head-tube and the paper-tube, and one by which the destructive action normally occurring in these shells shall be reduced and thereby secure an increased 20 durability and a more extended period of serviceability.

For accomplishing those objects, I have devised a composite shot-shell having, as hereinafter explained, a depressed panel extending 25 in a circuit and inclosing an undepressed zone within which are located a considerable number of relatively abrupt or sharp paper-engaging devices for gripping the paper-tube within a zone thereof which 30 is relatively segregated from the main portion of such tube by a compressive controlling action of the circuit-form panel of the metal head-tube, and in which this peculiar action is of a relatively non-destructive 35 character.

My present invention, therefore, is in part in the nature of an improvement upon the interlocking construction disclosed in Letters Patent of the United States, No. 1,020,142, granted to me March 12, 1912, for paper shot shell, in which a non-circumferential depressed panel is shown extending only partially around the shell, and only in a single position longitudinally of the shell, and without any supplemental metallic paper-engaging projections, and with no paper-engaging faces or devices located on an undepressed portion of the head-tube, and with no such faces or devices separated from the depressed panel.

In the drawing accompanying and forming a part of this specification, Figure 1 is a side view of a paper-tube shot-shell made according to my present improvements; Fig. 2 is a longitudinal sectional

view through the center-line of the shell; Fig. 3 is a cross-sectional view in the line X-X, Fig. 1; Fig. 4 is a developed view of the forward portion of the metallic head-tube, and is drawn in alinement with the 60 same part in Figs. 1 and 2, for more clearly illustrating the two circumferentially disposed depressed panels which are located, respectively, in separated longitudinal positions and are connected to form a circuit 65 inclosing an undepressed zone of the metal shell, and for showing the location within said inclosed or intermediate zone, of paper-engaging inwardly-extending projections separated from such zone-inclosing panel; 70 Fig. 5 is an enlarged sectional view (corresponding to a portion of Fig. 2) taken on the line Z-Z, Fig. 4; and, Fig. 6 is a fragmentary view (similar to Fig. 4 in arrangement) showing a portion of the 75 paper tube and illustrating the manner in which the outer surface is molded by the corresponding shapes of the head-tube.

Referring to the drawing, two circumferentially-disposed panel members, P¹, P², 80 are shown located, respectively, in different positions longitudinally of the metallic tube-portion B of the cartridge head H. In practice the head H may be of any usual or suitable construction, and I have therefore, for convenience, represented in the drawing, the construction shown in my aforesaid prior patent. The paper tube, T, is shown located within the metal tube B, and the rearward end is shown firmly seated 90 between the head H and the lining L, this being expanded outwardly by the usual base-wad W. In some cases the lining L may, if desired, be extended to a point forwardly of the panel-member P¹, or even beyond the tube B, as indicated, for instance, at 1, Fig. 2.

In Figs. 1 and 4, the two circumferential panel-members P¹ and P²,—these being separated by a considerable distance,—are shown connected by the relatively longitudinal panel-members P³ and P⁴, and thus the depressed panel becomes a circuit which as a whole extends around and incloses the undepressed tube zone N. For convenience, 105 the panel, considered as a whole, is designated by P. The preferred construction of the panel P is indicated in Figs. 2 and 5, particularly in Fig. 5, where it is shown composed of the depressed central portion 3, 110

connected by the two ogee-curves, at 3^a and 3^b, with the undepressed tube wall, at 2^a and 2^b, on either side. When the fibrous paper-tube T is forcibly expanded by the 5 gas pressure, (see Fig. 5) the depressed panel P is embedded into the paper tube-wall, at 4, with the result of forming therein a channel as C, Fig. 6, and of reforming and molding the fibers in curvilinear directions, in a manner diagrammatically indicated at 4^a, 4^b, doing this with a compressive action tending to control the sliding tendency of the tube T within the tube B, and with a minimum of destructive 10 action. In this class of reloadable shot-shells, as I have discovered and experimentally ascertained, the fibrous material of which the paper-tube, T, is made, is adapted for being moderately compressed 15 without injury in relatively narrow zones or areas, and into an interlocking engagement with inwardly-extending or depressed shell-wall zones or panels when these have an ogee sectional form,—especially such as indicated in Fig. 5,—the fibers being thereby 20 molded or formed on curved lines in a peculiar manner which permits and secures the required yielding action of and within the body of the paper-tube material, and among 25 the fibers thereof, while obtaining a suitable compressive and gripping interlock action, as between the metal tube and the paper tube for resisting both the longitudinal and the torsional stresses to which these tubes 30 are liable, and to which they are normally subjected, first during the firing of the charge, and later, during the extraction of 35 the shell. In this connection it will be remembered that on the firing of the powder charge, the earlier stages of the increasing 40 gas-pressure operate to forcibly expand the paper tube T against the inner surface of the gun-barrel, (not shown), and thereby resist by a firm adhesion any sliding of this 45 shell-tube in the barrel; and that subsequently to such adhesion becoming effective, and when the increase of the gas-pressure comes to nearly its maximum, the metallic head of the shell is driven backwardly 50 through a distance which in practice is permitted by the unavoidable yielding of the component members of the gun-mechanism under such maximum pressure, thereby forcibly drawing the head H rearwardly, 55 and tending to tear the head away from the paper tube. This action, however, being resisted as above indicated, and the usual base-wad being compressed into place for holding the rearward end of the paper tube T, 60 firmly engaged with the head-member H, results in applying an intense stress to all that rearward part of the paper tube which is within the tube B of said head-member; and this action appears to be especially severe 65 throughout the length of the circum-

ferential zone n, as from n¹ to n², Fig. 2, within which zone the described gripping and interlocking features are located. It will now be evident how the panel-circuit P, by being embedded in the tube T, forms 70 therein a compressed zone, as C, also in the form of a circuit, and thus divides off and partially separates from the surrounding tube-surface, an inclosed interlock-zone or area, as N¹, Fig. 6, which is thus brought 75 under a positive yet slightly yielding control by the described compressive action. Within that relatively segregated area, N, I locate in the tube B, a considerable number 80 of variously arranged and separated paper-engaging projections,—such for instance as D,—which project inwardly from the undepressed part, N, of the metal tube, and are separated from the panel P, so that these supplemental tube-gripping devices have a 85 direct engagement in and with the channel-inclosed full-thickness part N¹, Fig. 6, of the paper-tube T. In cross-sectional form these gripping members, D, are preferably formed with relatively sharp or abrupt side surfaces,—see Fig. 5,—for readily entering the firm fiber-stock of which the tube T should, in practice, be made and, preferably, also those projections D should be of a greater height inwardly from the 90 tube-wall B, than is the panel P. The side faces of the said paper-engaging projections D are preferably of an ogee form, but having these of a sharper curvature than the ogee outer and inner side-boundaries at 3^a and 3^b, 95 respectively, of the panel P. Thus the circuit-form panel P of ogee-sectional form is 100 supplemented by a plurality of non-circuit-form ogee paper-gripping projections located within the circuit of the panel P, but 105 separated therefrom.

In the composite arrangement as above set forth, the fibers of the paper are in part pressed more firmly together and in part remolded or shifted to conform the paper 110 wall to the curved metal surfaces, especially to the double-ogee form of the compressive panel P. In this way I avoid any forcing outwardly of the paper into recesses or grooves as heretofore sometimes attempted, 11 because I find that such forced-out paper-projections are not of the desired strength and stability. In the present improvement, therefore, I have devised the different and more effective compound interlock-construction herein illustrated and described, in 12 which the interlocking engagement is largely effected by the narrow ogee-members, as D, which project inwardly directly from the head-tube itself, (and not from any non-aligned portion or panel thereof) and which engage with molded surfaces which are located wholly within the cylindrical boundary surfaces of the paper tube. This construction has the advantage of forming a 13

continuous and unbroken bearing-line, or line of demarcation as between the inclosed interlock-zone areas of the paper-tube, as N¹, and the surrounding plain cylindrical surfaces, as clearly indicated in Fig. 6. Thus the group D of said paper-gripping members all act upon an area of the paper-tube which is already inclosed within a circuit-zone which is under compression, and consequently the effect of these inclosed members, D, is also restricted within such circuit, so that a relatively large number of those non-circuit form of ogee members may be used, sufficient for securing the necessary aggregate extent of the interlocking action and to prevent undue longitudinal or torsional dislocation, and without thereby materially impairing the strength of the tube T.

The manner above described of combining together or grouping a plurality of the non-circuit-form members within a circuit-form ogee-member,—the forms being arranged or included within the circuit of the latter,—has the further advantage of permitting the zone P of the metal shell B, to be so proportioned as to be able to successfully resist deflection from being repeatedly subjected from within to the gas-pressure of high-power explosives. The several non-circuit ogee-members, as D, should all be made, in practice, of a narrow width, the inclosed area N of said metal shell being made with the major portion of its exterior surface coincident with the exterior cylindrical surface of the member B, so that the said inclosed area when the cartridge is fired will bear normally and directly against the barrel of the gun. By thus avoiding the use of any non-aligned form of panel for carrying the ogee-form of curved paper-engaging faces, the desired aggregate amount of interlocking is readily obtained, and in a manner least destructive to the paper-tube, since the curved metal surfaces act by molding rather than by incising the surface fibers of the paper, while the avoidance of sharp angles further provide for the required amount of mobility, with a minimum of wear in the interlock-zone due to such action or mobility.

In Fig. 5, I have indicated a peculiar feature of the operation or coaction of the inter-engaging faces of the two tubes B and T, during the time when the inner tube is subjected to gas-pressure and is also subjected to strain longitudinally by the rearwardly yielding movement of the outer tube B. The paper-tube T being held in place by the pressure within the forward part thereof, is resistant to rearward movement in the gun-barrel (not shown) as indicated by the arrow 6, while the same pressure drives the metal tube B rearwardly, as indicated by the arrow 7. This action results, of course, in putting the paper-tube T under a longitudinal tension (as also indicated by

said arrows 6 and 7), and in forcing the ogee-member P rearwardly against the paper at 4^a where the increased density thereby momentarily created is indicated in Fig. 5 by the darker shading at that point. But 70 a further and peculiar action also takes place at that location, since the concave curve e of the ogee-wall 3^a now acts to guide or deflect the fibers inwardly toward the convex-curve e¹ of such ogee-surfaces, and so reduces the force of the interlock-engagement as between the two tubes, to a point or amount sufficient to prevent any substantial impairment of the stability of the paper tube T at that location therein, and thereby 80 maintaining an effective interlock while avoiding the high ratio of destructive action and consequent rapid deterioration heretofore usual in this general class of shot cartridges.

A further and immediate effect of the foregoing actions is to cause the ogee-walls, as 3^a, 3^b, Fig. 5, to bear against and tend to crowd or ride over the opposing bearing faces, as 4^a, 4^b; but these latter faces being fibrous and though curved having a surface continuity, the forces thus applied operate to compress the fibers, (as approximately indicated by the shading) in one of said locations, as 4^a, while relieving or reducing such pressure on the opposite walls or faces as indicated by the lighter shading at 4^b. Thus the operations here set forth have the normal effect of causing a sliding tendency of the interlocking zone of the paper-tube with an accompanying modification in the actual locations in the tube-wall of the described areas of high compression and of relatively low compression. By reason of the continuity of the paper tube-surface, and the ogee form of the opposing interlocking faces, the bended fibers in said pressure areas are naturally subjected, during the period of the said stresses and sliding action, to a shifting of form and relative positions, these results 100 being facilitated, also, by the qualities of toughness and resiliency of the fiber-stock of which the tube T should be formed.

With the relatively incipient gripping action,—or, more properly, compressive action,—resulting from the panel section with its ogee curvature pressed only a moderate depth into the paper, yet sufficient to firmly engage the paper tube; and with the numerous engaging members located within 115 the described panel-inclosed or intermediate zone, as N, and shaped for more positively gripping into the paper of the tube T, this tube may be said to have a progressive engagement with the head-tube B while under 120 the gas-pressure, first, the direct frictional engagement outside of the circuit of the panel, second, a moderate compressive-engagement in the circuit of the panel, and, third, the more positive additional engage- 125 130

ment of the numerous interlock or gripping devices located and distributed within the panel-inclosed zone. The said fibers and pressure areas are thus shifted in the tube wall T in one direction during the period of increasing gas-pressure, and on the reduction of this pressure, those shifted parts are restored to substantially their original locations by a forward movement of the head member H, while the forward portion of the paper-tube remains in its original position in firm adhesion with the bore-surface of the fire-arm. That forward movement of the head-member H, will, of course, be substantially the amount of the preceding rearward movement thereof due to any flexing of this head member plus the amount of the yielding of the breech-block or other parts of the gun, which thus operate for the moment as an actuator for so restoring the shell members to their original positions, the one relatively to the other, and without any considerable or material injury to the surface-fibers of the paper-tube, so that the reloadable shells may now be used a large number of times before becoming so greatly worn as to be unserviceable.

Having thus described my invention, I claim:—

1. In a paper-tube shot-shell, the combination with a head having a metal tube extension for inclosing the paper-tube, of the paper-tube fixed at one end in the head and extending within and beyond the head-tube, and a compound interlocking construction comprising a continuous circuit-form depressed panel formed in and extending around the head tube less than one circumference thereof, and inclosing an undepressed zone of the head tube located between two circumferentially-disposed panel-portions which are located in different positions longitudinally of the head-tube, and also comprising a plurality of paper-engaging projections extending inwardly from said inclosed head-tube zone and located in positions separated from each other and also separated from said depressed panel, whereby said projections engage in and interlock with the paper-tube within a zone of the paper-tube which is inclosed within a compressed circuit-form zone which engages with said depressed circuit-form panel of the head-tube, and whereby this panel has

two circumferentially-disposed zones of compressive engagement with the paper-tube located, respectively, at two different and separate positions longitudinally of the head-tube, substantially as described.

2. In a paper-tube shot-shell, the combination with a head having a metal tube extension for inclosing one end of the paper-tube, of the paper-tube fixed in the head and extending within and beyond the head-tube, and a compound interlocking construction comprising a depressed zone-inclosing paper-compressing panel formed in the head tube and inclosing an undepressed zone of the head tube between two circumferentially-disposed panel-portions which are located in different positions longitudinally of the head-tube, and also comprising a plurality of paper-gripping interlocking-projections extending inwardly from said inclosed head-tube zone and located in distributed positions separate from each other and also separate from said depressed panel, for engaging in and positively interlocking with the paper-tube within one zone which is located between two circumferentially-disposed zones of compressive engagement located, respectively, at two different and separated positions longitudinally of the paper-tube and within the head-tube, substantially as described.

3. In a shot shell, the combination with a paper-tube, of a head having fixed therein one end of the paper tube, and having a tubular extension surrounding the paper tube and having a depressed panel formed in and extending around the said head tube less than one circumference thereof, and having an undepressed intermediate zone of the head tube located between two circumferentially-disposed panel-portions which are located in different positions longitudinally of the head-tube, and also having a plurality of paper-engaging projections extending inwardly from said head-tube intermediate zone and located in distributed positions separated from each other and also separated from said panel, substantially as described.

FRANK O. HOAGLAND.
